DESIGN FOR A DRINKING CUP

Robert M. Schiller, Chicago, Ill.

Application December 15, 1932. Serial No. 46,466

Term of patent 7 years

To all whom it may concern:

Be it known that I, ROBERT M. SCHILLER, a citizen of the United States, residing at Chicago, in the county of Cook and State of Illinois, have invented a new, original, and ornamental Design for Drinking Cups, of which the following is a specification, reference being had to the accompanying drawing, forming a part thereof.

Fig. 1 is the front elevational view of the cup showing my new design.

Fig. 2 is a bottom plan view of the same.

I claim:

The ornamental design for a drinking cup, substantially as shown.

ROBERT M. SCHILLER.
